INVENTOR.

BY *D. V. Cunning*
Watson E. Coleman
ATTORNEY.

UNITED STATES PATENT OFFICE.

DONALD V. CUNNING, OF YOUNGSTOWN, OHIO.

BODY BRACE.

Application filed November 17, 1923. Serial No. 675,403.

To all whom it may concern:

Be it known that I, DONALD V. CUNNING, a citizen of the United States, residing at Youngstown, in the county of Mahoning 5 and State of Ohio, have invented certain new and useful Improvements in Body Braces, of which the following is a specification, reference being had to the accompanying drawings.

10 This invention relates to certain improvements in body braces and has relation more particularly to a device of this general character especially designed and adapted for use in connection with the shoulders and 15 upper portion of the body and it is an object of the invention to provide a novel and improved brace including a belt portion adapted to be disposed around the hips just below the crest of the ilium or more particularly about one inch below the protruding points of the hip bones whereby the belt portion is prevented from slipping up and resulting in an added brace to the entire upper portion of the body.

20 Another object of the invention is to provide a novel and improved device of this general character formed from strips of pure gum rubber whereby the device adheres with firmness to the flesh or clothing.

25 Another object of the invention is to provide a device of this general character possessing great elasticity and strength combining to hold the shoulders and body erect yet offering no hindrance or obstruction to the perfect freedom of every muscle.

30 An additional object of the invention is to provide a novel and improved device of this general character possessing requisite stretch with a powerful come-back, two features essential to rendering the device both comfortable and effective.

35 It is also an object of the invention to provide a novel and improved device of this general character which is sanitary and which does not bind under the arms thereby leaving the armpits entirely free from pressure.

40 Furthermore it is an object of the invention to provide a novel and improved device of this general character embodying in its structure what may be termed a block and tackle adjustment whereby the device may be used with a maximum of efficiency to effectively brace the body and particularly the shoulders.

45 The invention consists in the details of

construction and in the combination and arrangement of the several parts of my improved body brace whereby certain important advantages are attained and the device 50 rendered simpler, less expensive and otherwise more convenient and advantageous for use, as will be hereinafter more fully set forth.

The novel features of my invention will 55 hereinafter be definitely claimed.

In order that my invention may be the better understood, I will now proceed to describe the same with reference to the accompanying drawings, wherein:

60 Figure 1 is a view in perspective of the brace constructed in accordance with an embodiment of my invention unapplied;

65 Figure 2 is a detailed sectional view taken substantially on the line 2—2 of Figure 1;

70 Figure 3 is a front elevational view of the device applied, the coacting body being diagrammatically indicated;

75 Figure 4 is a view in side elevation illustrating the device applied, the body being diagrammatically indicated;

80 Figure 5 is a rear elevational view showing the device applied, the body being also diagrammatically indicated.

85 My improved brace as herein disclosed comprises an elongated strip of material preferably pure gum rubber, said strip at its central portion constituting a short member 1 continued by the inwardly and upwardly extended members 2. The portions 90 of the members 2 and the adjacent portion of the member 1 being connected, as at 3, to provide the loops 4, the outer walls of said loops 4 being disposed on downward and inward inclines with respect to the member 1. Engaged within the loops 4 are the buckles 5 of desired type and through which are freely directed the continued portions 6 of the members 2, said continued portions 6 providing loops adapted to be engaged over the shoulders of the wearer, said loops being readily adjustable as to size by requisite slippage of the portions 2 through the buckles 5.

95 The members 2 have their converging end portions in overlapping relation and are suitably connected one to the other as at 8.

100 One extremity of the strip is provided with a buckle 9 preferably of the type generally employed in connection with an ordinary belt and with which is adapted to be engaged the second extremity of said

strip as is clearly illustrated in Figures 1 and 3 of the accompanying drawings.

The portions 7 of the strip outwardly of the buckles 5 are provided with the longitudinally spaced openings 10 whereby may be adjustably connected, as at 10', there with the extremities of the belt or body encircling members 11 of elastic material and also preferably pure gum rubber. These members 11 extend one across the other and the overlapping portions thereof are secured together, as at 12, said overlapping portions of the members 11 are provided with the longitudinally spaced openings 14 whereby the connection 12 may be adjusted as the requirements of practice may necessitate. The extremities of the members 11 are also secured, as at 15, to the portions 7 of the strip at desired points inwardly of the extremities thereof, the end portions of the members 11 being provided with the longitudinally spaced openings 16 and the adjacent parts of the portions 7 being also provided with the longitudinally spaced openings 17 whereby such connections 15 may be adjusted as required.

The portions 6 of the strip outwardly of but in relatively close proximity to the connection 8 have interposed therebetween and secured thereto the strip 18 of elastic material preferably of pure gum rubber.

The connecting or fastening means 10', 12 and 15 may be of any type preferred whereby the requisite adjustments may be obtained although as herein disclosed each of such means comprises a headed shank 20 with which is detachably engaged a holding plate 21.

In practice, the loops 6 are engaged over the shoulders with the buckles 5 below the shoulder blades, the patient is then caused to throw back the shoulders and expand the chest to the utmost when the strip is gently pulled through the buckles 5 to adjust the same to the body and at the proper tension. In applying the device, the member 1 and strip 18 are at the back with the member 1 adjacent to the small of the back. The portions 7 of the strip are then extended forwardly around the body and secured, with their extremities connected together, in front just below the crest of the ilium. While the members 11 are extended forwardly around the body and suitably secured to the portions 7, said members 11 preferably extend one inch below the protruding points of the hip bones to prevent said members 11 and the adjacent portion of the device from slipping upwardly of the body and to give added brace to the entire upper portion of the body.

By having the various members or strips formed of pure gum rubber, the device will adhere to the flesh or to the clothing much firmer than when made of other material and also provides strength and great elas-

ticity combining to hold the shoulders and body erect yet allowing perfect freedom of every muscle in the body. The device as herein disclosed has stretch and a powerful come-back, two essential features to assure the device being both comfortable and effective.

The device is also highly sanitary as it can be readily washed and is also durable and light in weight making the brace effective for children as well as adults. The device as herein disclosed does not bind under the arms as the portions 6 do not encircle the arms thereby leaving the armpits entirely free from pressure.

The structure as afforded by the buckles 5 provides what may be called a "block and tackle pull" below the shoulder blades whereby the device is highly effective for the purposes desired.

From the foregoing description it is thought to be obvious that a body brace constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A brace of the class described comprising an elongated elastic strip having its central portion providing a short member, the extremities of said member being continued by upwardly and inwardly disposed members one crossing the other at a point closely adjacent to the short member, means for connecting said second named members adjacent their junctions to the short member to provide loops, buckles engaged within said loops, said second named members being continued and disposed through the buckles to provide loops adapted to be engaged over the shoulders of the wearer, means for connecting the overlying portions of the second members, means for adjustably connecting the free extremities of said second members, the portions of the second members outwardly of the buckles being adapted to be disposed forwardly around the body of the wearer for connection in front just below the crest of the ilium, and a strip secured to each of said members outwardly of the buckle through which said member is disposed and to the other of said second named members at a point outwardly of the buckle through which the other of said second named members is directed.

2. A brace of the class described comprising

ing an elongated elastic strip having its central portion providing a short member, the extremities of said member being continued by upwardly, and inwardly disposed members one crossing the other at a point closely adjacent to the short member, means for connecting said second named members adjacent their junctions to the short member to provide loops, buckles engaged within said loops, said second named members being continued and disposed through the buckles to provide loops adapted to be engaged over the shoulders of the wearer, means for connecting the overlying portions of the second members, means for adjustably connecting the free extremities of said second members, the portions of the second members out-

wardly of the buckles being adapted to be disposed forwardly around the body of the wearer for connection in front just below the crest of the ilium, a strip secured to each of said members outwardly of the buckle through which said member is disposed and to the other of said second named members at a point outwardly of the buckle through which the other of said second named members is directed, said last named members crossing at the rear of the device, and means for connecting the overlying portions of said last named members.

In testimony whereof I hereunto affix my signature.

DONALD V. CUNNING.
